2,376,602

GLASSWARE FORMING MACHINE

Clarence C. Kinker, Montreal, West, Quebec, Canada, assignor to O'Neill Patents Limited, La Salle, Quebec, Canada, a corporation of Quebec

Application January 20, 1942, Serial No. 427,439

17 Claims.

(Cl. 49—9)

This invention relates to improvements in glass-ware forming machines of the type including blank and finishing or blow mold tables arranged side by side for rotation about separate vertical axes, and more particularly to machines of this type in which said tables are rotated intermittently or in a step by step manner.

One object of this invention is to produce a glassware forming machine in which the mold carrying tables are intermittently rotated and in which each blank or parison mold has its bottom or large end up, with its neck forming portion down, at the charge receiving station, and is uprighted prior to making the transfer to a blow mold while the tables are moving at or near their lowest peripheral speed, whereby the various mechanisms for uprigting the blank mold to position with the neck forming portion up, and for transferring the parisons from blank to blow molds are positively operated by cam mechanisms.

Another object is to produce a novel and improved baffle plate and blow down mechanism for cooperation with the blank molds of glass forming machines.

A further object is to produce an improved and simplified mechanism for obtaining individual blowing control not only for the parison packing and bubble blow, but for the blow of the finished bottles or ware.

A still further object is to produce an intermittently operating glass forming machine in which the mold charges are delivered to the blank molds during the rest periods and in which the operations, including transfer of parisons to blow or finishing molds are controlled and operated by cams during indexing periods of the machine and at or near the slowest movements of the machine during such periods.

These and other objects, which will be apparent to those skilled in this art, are attained by means of the mechanism described in the specification and illustrated in the drawings accompanying and forming part of this application.

In the drawings:

Figure 1 is a view partially in section and partially in elevation of the blank mold table of a machine embodying this invention. This view is taken on line I—I of Fig. 7;

Fig. 2 is a more or less diagrammatic skeleton view partially in elevation and partially in section illustrating the valves and lines for controlling the application of vacuum to the blank molds, the application of air for packing the glass around the mouth forming pin and the application of

air for accomplishing the bubble blow or parison forming operation;

Fig. 3 and 4 are respectively central vertical and horizontal sectional views on an enlarged scale of the air distributor valve mechanism for obtaining flow of air for packing the glass around the mouth forming pin and to form the finish. Fig. 3 is taken on line III—III of Fig. 4 and Fig. 4 is taken on line IV—IV of Fig. 3.

Fig. 5 is a diagrammatic view in top plan and discloses the stations of the blank mold table, the opening and closing of the blank molds, the swinging of the baffle assembly to and from operative position and the timing of different parts of the mechanism;

Fig. 6 is a developed view of the cam for raising and lowering the baffle assembly;

Fig. 7 is a more or less diagrammatic top plan view of a number of the cams entering into the make-up of the blank mold table of Fig. 1. This view includes a top plan view of a portion of a closed blank mold and its associated neck mold and a view in horizontal section taken on line VII—VII right-hand half of Fig. 1, and illustrates portions of a blank mold and the mechanism for opening and closing the same;

Fig. 8 is a perspective view of the cams which control the application of vacuum and the bubble blow and is taken as though looking from line VIII—VIII of Fig. 7 in the direction of the arrows;

Fig. 9 is a fragmentary enlarged sectional view of a blank mold unit, the baffle assembly and its operating mechanism and shows a fully formed parison in place in the blank mold. This same mechanism is shown in the left-hand portion of Figure 1.

Fig. 10 is a more or less diagrammatic view looking up toward the under side of one of the neck ring or neck mold units and its operating cam;

Fig. 11 is a view partially in section and partially in elevation of the blow table of the machine of this invention and is taken on line XI—XI of Fig. 12;

Fig. 12 is a fragmentary top plan view of the blank and blow mold tables of the machine and illustrates the location of the takeout device;

Fig. 13 is an enlarged detail view partially in section and partially in elevation and shows an open blank mold, a blank or parison suspended by the neck ring or mold and a blow mold which is closing around the parison adjacent the transfer station or point.

Fig. 14 is an enlarged fragmentary top plan

view of a finishing mold unit and its individual adjustable cam for controlling its air supplies;

Fig. 15 is a longitudinal sectional view of such individual valve and is taken on line XV—XV of Fig. 14;

Fig. 16 is a fragmentary detail view looking up toward the bottom thereof of a portion of the valve mechanism of Fig. 15;

Fig. 17 is a view partially in elevation and partially in transverse section of part of the valve mechanisms of Figs. 15 and 16 and is taken on line XVII—XVII of Figure 15;

Figs. 18, 19 and 20 are views partially in top plan and partially in section showing successive positions of the mechanism for opening and closing one of the blow or finishing molds. Fig. 18 shows the mechanism in position to apply closing pressure to the blow or finishing mold. Fig. 19 shows the mechanism in position to hold the mold closed, but without application of extreme closing pressure, and Fig. 20 shows the mechanism in position to hold the mold open.

Fig. 21 is a fragmental and more or less diagrammatic view of the periodic motion mechanism by which the machine is driven; and

Fig. 22 is a fragmental side elevation of such periodic motion mechanism.

The machine chosen for illustrating this invention is adapted to receive measured charges or gobs of glass delivered to it at regular timed intervals by any well known and suitable feeder device.

The mold tables are geared together so as to rotate in unison and in opposite directions, and, in order that such rotation may be accomplished periodically or in a step-by-step manner, with such periodic movements of equal length and of equal time duration, I preferably utilize a periodic motion drive mechanism disclosed in Figures 1 to 9 inclusive of my United States Patent 2,298,215, granted on October 6, 1942, on an application filed August 2, 1940.

Since the mold carrying tables are geared together it is only necessary to employ one of the periodic motion devices of said patent. The blow or finishing mold table is provided with two sets of cam contact rollers for co-operating with the form of device of Figs. 1 to 9 inclusive of my said patent. By utilizing such a device for driving this table, I am able to control the periodic movements of both tables so that they are both accelerated from their stop positions to maximum speed and then decelerated from maximum speed to the next stop position without appreciable shock to the mechanisms involved. Since each table carries six mold units, there are six stop positions.

As each blank mold arrives at the charging station, the tables are stopped and the blank mold at such station, with its neck end down and its open bottom end up, receives a charge or gob of glass which is guided thereto by means of a stationary funnel. When the charge has entered the mold, it is compacted in the neck ring around the mouth forming pin, first by subjecting the lower end of the mold and neck ring around said pin to a vacuum, and, shortly thereafter by supplying air under pressure to then upper (bottom) end of the mold which at this time has been closed by the baffle plate guide.

As soon as the charge packing has been accomplished, the baffle plate is lowered within its guide into contact with the upper end of the mold (the bottom end). The neck pin is then slightly retracted and the compacted charge of glass is

10 elongated into a parison while confined in the blank mold. This is done by forming therein the usual "bubble" which is sufficient to elongate the charge to give to the parison the desired length for final blowing in the blow or finishing mold.

Between the time the parison or blank is completed, and the transfer station is reached, the parison mold is uprighted so that when it reaches the transfer station, it is in upright position, that is, with its neck forming portion up.

Just prior to the tables' stop at the transfer point, and while the tables are moving at a relatively slow speed, the parison or blank is transferred to the blow mold which is then in open position and is approaching the transfer point.

20 The blank or parison molds and the finishing molds move in closed paths which intersect at a common transfer point, and, just prior to the time a pair of such molds reach this point, the parison mold is positively opened by cam means, leaving the parison suspended by the neck ring. The blow mold then closes around the suspended parison and the neck ring is then positively opened by cam operated means and the parison is released to the blow mold as it closes about the same. The transfer is all effected before the tables stop at the station just beyond the transfer point.

25 The final blowing of the ware is accomplished during movement of the finishing molds from the transfer point to the discharge point. During this time the blown ware has become sufficiently set and self-sustaining to be engaged by the take-out mechanism, and I preferably employ a take-out mechanism such as disclosed in U. S. Patent 1,537,963 granted to Frank O'Neill on May 19, 1925.

30 The blank or parison mold table, which as an entirety is numbered 25, is mounted for rotation about a vertically extending column 26 while the blow or finishing mold table, which as an entirety is numbered 21, is mounted for rotation about a vertically extending column 28. These columns are secured to a part 29 of the base of the machine with which they make tight contact since both columns are hollow and serve as storage chambers for air under pressure.

35 The blank or parison mold table comprises a lower dished spider-like member 30, an upper table-like member 31 and an intermediate member 32. These members are connected together so as to rotate as a unit about column 26 and are supported by an anti-friction bearing 33 carried on a shoulder formed on column 26 as shown in Fig. 2. A ring gear 34 encircles and is preferably formed as an integral part of lower dished spider-like member 30.

Blank mold units

40 The blank mold units, one of which with its neck ring and a portion of its operating mechanism is shown in Fig. 9, are carried by intermediate member 32 in such a manner that each blank mold as it reaches the charging station will have its open bottom end up ready to receive a charge of glass, and, as it reaches the transfer point will have its neck end up with the parison or blank in position to be transferred to a blow or finishing mold.

45 Each blank mold unit comprising a portable body mold 35 carried by a pair of support arms 36 which are pivotally connected to a hinge pin 37, and a portable neck ring or mold 38 which is carried by a pair of support arms 39 which are also pivotally connected to hinge pin 37.

Each hinge pin 37 forms part of a turnover unit and is rigidly secured within ears 48 and 49 of head 42 of a turnover drum 43, which is included in such turnover unit. This turnover drum is journaled in a bearing member 44 having its longitudinal axis extending radially of blank mold table 25. A flange 45, extending radially outward from the outer end of the turnover drum, carries an annular series of rollers 46 which are adapted to engage notches or recesses 47 formed in the lower surface of an arcuate cam member 48 which is secured to a stationary cam carrier 49. This cam carrier is rigidly secured to column 26, and not only supports arcuate cam member 48, but also supports the cams for controlling the opening and closing of the blank and neck molds.

Each turnover unit is arranged to be locked in its two operating positions by means of a lock bar 50 which is mounted for reciprocation within a horizontally extending guideway formed in a bracket later referred to as bracket 98. This guideway is covered by the lower face of member 32. The outer end 51 of lock bar 50 is tapered and is adapted to co-operate with diametrically opposed notches 52 in flange 45 of the turnover drum.

Each lock bar 50 is pivotally connected to the upper end of a lever 53 and such lever is mounted for swinging movement about a centrally located pivot pin 54. This pin is journaled within brackets 55 carried by spider member 30. Each lever 53 adjacent its lower end carries a cam contact roller 56 which bears on a stationary cam 57 rigidly secured to the shouldered portion of column 26 which carries anti-friction bearing 58. This cam is provided with diametrically opposed lobes 59 and 60 (Fig. 7), which cause each lock bar 50 to be moved by its lever 53 to its unlocking position against the stress of coil spring 60, which is interposed between the inner end portion of said lock bar and the adjacent spring support 61 secured to the hub portion 62 of intermediate member 32.

Each body blank 35 is opened and closed independently of its associated neck ring, by mechanism such as illustrated in Figs. 1 and 7 and which is partially located within drum 43 of the associated turnover unit. This mechanism includes a horseshoe-shaped member or yoke 63 which is spaced inwardly from the blank mold and is connected to the blank mold body sections by means of links 64.

A pull rod 65 which extends through an opening in yoke 63, has a head 66 at its outer end, and, at its inner end is threaded into a slide block 67. This slide block is counterbored so as to telescope over a sleeve-like end 68 of the yoke. A coil spring 69 surrounds the pull rod and has one end bearing against the yoke and the other end against a thrust bearing 70 located at the inner end of the counterbore in the slide block. The spring yieldingly holds the head 66 of the pull rod in contact with a shoulder 68a which surrounds the opening in the yoke through which the pull rod passes. Proper positioning of the yoke is thus obtained.

Slide block 67 is arranged to slide within gibs toward and from column 26. These gibs are formed in a bearing support member 71 which is carried by table member 32. The slide block carries a cam roller 72 which cooperates with a stationary cam 73 to open and close the body sections of the blank mold. Excess movement of the slide block is taken care of by spring 69 so that when the full throw of the cam is reached,

head 66 of the pull rod will move outwardly away from shoulder 68a. This arrangement is provided in order to take care of any discrepancies in machine work and/or wear of the parts, and provides a yieldable connection between slide block 67 and yoke 63 for preventing damage due to excess glass or other foreign matter which may be caught between the blank mold halves. Thrust bearing 70 permits spring 69, yoke 63 and the drum within which the yoke is located, to be rotated about pull rod 65 by means of rollers 46 and cam grooves 47.

From the above it will be seen that sufficient outward motion of slide block 67 causes the blank mold body sections, through the agency of spring 69, yoke 63 and links 64, to be moved to closed position as shown in Figs. 1 and 9, and that sufficient inward movement of slide block 67 causes the blank mold body sections, through the agency of headed pull rod 65, yoke 63 and links 64, to move to open position as shown in Fig. 7.

Cam 73 is of composite character, that is, extending in a counterclockwise direction from point 73a to point 73b it is merely a plate cam with its surface concentric with column 26, while extending in a counterclockwise direction from point 73b to point 73a, it takes the form of a positive motion cam by including in its make-up an outer wall 74, with which roller 72 contacts in its travel about column 26. As roller 72 contacts with cam 73 while traveling in a counterclockwise direction from point 73a to point 73b, the body sections of the blank mold are held in closed position and while traveling from point 73b to point 73a, said sections are opened for transfer of the parison to the blow mold.

Neck ring 38 is normally held closed by means of a coil spring 15 which connects its support arms 39. Opening of the neck ring at regular time intervals is obtained by means of a spreader head 76 which is located within complementary depressions in the adjacent faces of said arms 39.

45 This spreader head is formed at one end of a pin 77 which is journaled for oscillation or rocking movement within a vertically extending bushing 78 pressed into a support bracket 79 which is keyed to the lower end of hinge pin 77, and also bolted to flange 45 of the turnover drum.

A spreader operating lever 80 has one of its ends secured by key 80' and clamp 80'' to the end of pin 77 remote from the spreader head. The opposite end of lever 80 is connected to a lever 81 by means of an adjustable turnbuckle 82. Lever 81 is pivoted to a post 81a carried by support bracket 79. Between its ends, lever 81 carries a roller 83 which is arranged to cooperate with a cam 84 in opening the neck ring at the proper time and in the proper manner.

60 Cam 84 is secured to cam carrier 49 adjacent the transfer point (Figs. 1 and 7).

Support bracket 79 carries the plunger unit which includes an outer vertically extending sleeve 85, fitted into an opening in bracket 79, and which is provided with conduits 86. A hollow plunger 87 which at its upper end carries mouth forming pin 88 extends below sleeve 85, and, at its lower end is provided with a nipple-like member 89 which is flanged as at 90 and confines and supports a coil expansion spring 91.

75 Plunger 87 is provided with channels 92 which connect its interior with the space which surrounds mouth forming pin 88. The plunger is also provided with a series of openings 93 which

connect with channels 88 when the plunger is in the position shown in Fig. 9.

Downward movement of plunger 87 is limited by a flange 94 and a cooperating shoulder 95 located near the upper end of sleeve 85.

Spring 91 retracts hollow plunger 87 with respect to sleeve 85 and neck ring 88, when such action is permitted by the means hereinafter to be described.

Application of vacuum for packing the glass into the neck mold around the mouth forming pin, and pressure air for accomplishing the bubble blow is obtained by means of a hollow vertically swinging arm 96. This arm is pivoted to a hollow trunnion-like member 97 carried by a bracket 98 (Fig. 1) which is secured to table 32. This hollow trunnion-like member connects with a valve housing 99 for an air valve 100 and with a valve housing 101 for a vacuum valve 102.

Air valve 100 of each unit is normally held closed by a coil spring 103, which surrounds its stem 104 below the valve casing or housing, and bears on an abutment 104a secured to said stem. A plunger 105 mounted to slide vertically within a guide 106 has a stem 107 threaded into a vertically extending opening in line with valve stem 104. Stem 107, which is in vertical alignment with valve stem 104 is provided with a cross pin 107a by means of which said stem may be manually turned in order to adjust the space or gap between the lower end of valve stem 104 and the upper end of stem 107. A lock nut and lock washer are provided as shown in the enlarged portion at the right of Fig. 2, for locking stem 107 in adjusted position.

Vacuum valve 102 is normally held in closed position by a coil spring 108 which is confined between the top of valve 107 and the top of valve housing 101. A plunger 109 mounted to slide vertically within a guide 110 has a stem 111 threaded into a vertically extending opening in line with valve stem 112. Stem 111, which is in vertical alignment with valve stem 112, is also provided with a cross pin 111a by means of which said stem may be manually turned to adjust the space or gap between the lower end of valve stem 112 and the upper end of stem 111. Stem 111 is also provided with a lock nut and lock washer as shown in the enlarged portion at the right of Fig. 2 for locking said stem 111 in adjusted position.

Each vacuum valve housing 101 is connected to the interior of column 26 by means of a pipe 113 and an annular chamber 114 which is formed in hub portion 62 of table 32.

Column 26 is provided with a series of openings 115 in line with annular chamber 114 so that as the blank mold table, made up of vertically spaced members 30, 31 and 32, rotates about column 26, pipes 113 are in constant communication with the interior of said column. This column 26 is sealed at its top by means of a cap 116, is tightly secured to base 29, and, by means of a pipe 117, is constantly connected to a suitable vacuum pump, not shown. Hollow column 26, therefore, facilitates rapid application of vacuum to the interior of swinging hollow arm 96, when the interior of said arm is placed in communication with the interior of column 26 by the opening of vacuum valve 102.

Each air valve housing 100 by means of a pipe 118 is connected to a hollow distributor ring 119 which surrounds and is carried by hub portion 62 of table 32. The effective area of each pipe 118

is made adjustable or, in other words, may be varied by a needle valve 120.

Hollow ring 119 is supplied with air under pressure by means of pipe 121 which connects with an air distributor head 122 carried by cap 116. This distributor will be described later.

Plunger 105 in line with the stem of air control valve 100 carries a roller 123 which cooperates with a cam 124 to raise the valve to open position at the proper time against the stress of its spring 103. Similarly plunger 109 which is located below and in line with the stem of vacuum valve 102 carries a roller 123a which cooperates with a cam 125 to open said valve at the proper time against the stress of its spring 108.

Each of the hollow arms 96 performs the two-fold function of establishing communication between valve housings 99 and 101 for the air and vacuum valves respectively, and the tubular plunger 87 which communicates with the mold cavities by way of channels 88; and of controlling the position of said plunger and therefore the position of the mouth forming pin 88 with respect to the neck ring.

It will be apparent that coil spring 91 retracts or withdraws plunger 87 and therefore mouth forming pin 88 from operative position within the neck ring when lever 96 and the blow head or sealing member 126 carried thereby are not pressing plunger 87 to the upper limit of its travel. It will also be apparent that the position of arm 96 directly determines the position of the mouth forming pin.

Movement of hollow lever arm 96 is obtained by means of a stationary cam 127 and a modified bell crank lever 128 with a cam contact roller 129 at its lower end. Lever 128 is pivotally mounted on a pad which is secured to member 30 of the blank mold table. At its upper end, this lever carries a sliding plunger 130 which is connected to lever arm 96 by means of a link 131. The plunger is yieldingly held to the outer limit of its travel by a coil spring 132 which is contained within the plunger housing 128a forming the upper arm of the lever.

With the parts in the position shown at the left-hand side of Figure 1 and in Figure 9, it must be assumed that pin 88 that forms the initial opening in the parison had been moved by hollow lever arm 96 and lever 128 into mouth forming position within the neck mold; that vacuum had been applied through arm 96 and hollow plunger 87 to the neck ring and body mold to pack the glass around the mouth forming pin, and that coil spring 91 had functioned to move the mouth forming pin 88 down to the bubble blow position shown in these figures.

It must also be assumed that the baffle plate 133 has closed the upper open end of the blank mold, that the glass packing flow has taken place, and that the bubble blow which elongates the parison has also been completed.

The baffle plate forms part of a baffle assembly which is carried by a lever arm 134. This lever arm in transverse section resembles an inverted U and so supports the baffle assembly that it may be moved vertically relative to the blank mold. Means, which includes an arm 135, is employed to swing lever arm 134 and the assembly carried thereby horizontally to different positions as shown in Fig. 5 of the drawings.

The baffle assembly

The baffle assembly includes an outer case 136 which in the main is cylindrical and which, sub-

stantially midway its length, is provided with oppositely positioned hollow pads for receiving pins 134a (one being shown by dotted lines in Fig. 9) by means of which said case is pivotally connected to lever arm 134. This lever arm at its outer end is bifurcated so as to straddle the outer end of arm 135 and its furcate parts are provided with openings for receiving said pins.

Outer case 136 is mounted for limited vertical sliding movement within upper and lower cylindrical portions 137 and 138 of arm 135. Threaded through an interior shoulder-like portion 139 of outer case 136 is a tubular stem-like member 140. This stem-like member adjacent its upper end is internally threaded to receive the hollow threaded stem 141 of a bolt 142.

The baffle plate is connected to the lower end of stem-like member 140 by means of a nipple 143. The baffle plate comprises a bottom former portion 144 having cross channels 145 which connect with the hollow interior of nipple 143, and therefore with the hollow interior of the stem of bolt 142, and vertical channels 146 which are located beyond the boundaries of the bottom former portion 144 of the baffle plate and connect with cross channel 145.

A baffle plate guide 147, formed in the nature of an inverted cup, surrounds the baffle plate and is mounted on the lower end portion of stem 140, for relative sliding movement with relation to said stem and therefore with relation to the baffle plate. An inturned flange 148 on the upper end of the baffle plate guide co-operates with an outwardly extending flange 149 at the lower end of stem 140 to limit the downward movement of the baffle plate guide with relation to stem 140 and the baffle plate.

A coil spring 150 surrounds the lower portion of stem 140, and, being confined between the upper end of baffle plate guide 147 and a horse-shoe-shaped washer or collar 151 which surrounds stem 140 below its external threads (see Fig. 9), tends to yieldingly hold the baffle plate at the limit of its outward movement, at which position its inturned flange 148 is in contact with flange 149.

The head of bolt 142, below its wrench portion 142a, is cylindrical and is provided with a circumferential groove 152 and one or more cross channels 153 which connect said groove with the interior of the bolt stem 141. A cylindrical sleeve 154 surrounds the cylindrical portion of bolt 142 and is provided with a tapped hole for receiving a nipple 155. This hole is aligned with the circumferential groove 152 of the bolt head. An air hose 156, secured to nipple 155, connects the air channels of the baffle assembly to the distributor head which is carried by plate 116 which seals the top of hollow column 26.

The threaded connections between stem-like member 140 and the outer case on the one hand, and between the hollow stem of the bolt and stem-like member 140, on the other hand, permit stem-like member 140, the baffle plate guide and the baffle plate, to be adjusted vertically to different normal positions in order to function with blank molds of different lengths.

It will be noted that the blank mold is provided with an upstanding beveled annular flange which surrounds its bottom opening and that the co-operating face 158 of the baffle guide is so formed as to make a combined sealing and clamping fit with such flange and thus locks the halves of the blank mold together.

It will be apparent that the bottom former por-

tion of the baffle plate may be of any desired contour so long as the baffle plate when in contact with the mold bottom, seals the interior of the mold for the bubble blow.

Baffle assembly supporting and operating mechanism

As above pointed out, the baffle assembly is supported by lever arm 134, is moved vertically to and from operative position by such arm and is swung horizontally to and from operative position by lever arm 135.

Lever arm 135 is mounted for horizontal swinging movement about a hollow cylindrical bearing member 159 which member is bolted to upper mold table member 31 (see Fig. 9). Lever arm 135 has bolted to it at its lower end a horizontally extending gear segment 160 which meshes with a rack member 161 (Fig. 5). The rack member is yieldably connected to a slide 162 by means of a bolt 163 which passes lengthwise through the rack member and is threaded into slide 162. A coil spring 164 surrounds the outer end of bolt 163 and is confined between the end of the rack member and a nut 165 threaded to the outer end portion of the bolt.

Slide 162 is mounted for sliding movement radially of the blank mold table and within a guideway 166 carried by upper member 31 of the table. The slide is provided with a roller 167 which moves in a double-faced stationary cam 168 formed as part of cam carrier 169 which is secured to column 26.

Lever arm 134 is pivoted to a post 170 by means of a pivot pin 171 which extends laterally through post 170 and into openings formed in the side portions of lever arm 134, which side portions are provided with outwardly extending pads 172 into which the ends of pin 171 extend.

As shown in Fig. 9, the head portion of post 170 is held in contact with the top of the cylindrical bearing member 159 for lever arm 135, by means of a coil spring 173. This spring surrounds the lower reduced end of said post and is confined in place by an end thrust washer-like member 174 and a washer-like retainer and end thrust bearing member 175. Coil spring 173 permits some vertical spring-restrained movement to post 170 and provides a safety device which allows post 170 to move upward in case baffle plate guide 147 fouls the blank mold flange 158 or in case some foreign object prevents the baffle guide 147 from moving down into clamping position around flange 158 of the body blank mold.

Lever arm 134, at its inner end, carries an adjustment screw 176. The lower end of this screw bears on the top of a plunger member 177 which is mounted for vertical sliding movement within a bushing 178 carried by member 31 of the mold table. At its lower end, plunger 177 carries a roller 179 which bears on the upper surface of a stationary cam 180. The vertical movement allowed plunger 177 is controlled by a pin and slot connection as indicated by dotted lines in Fig. 9.

Vertical swinging movement of lever arm 134, occasioned by cam 180, is yieldingly resisted by a coil spring 181 which is carried in a pocket formed in arm 135, and said spring bears against a pad formed on the web portion of lever arm 134; the upper end of the coil spring being centered by a pin 182 which is threaded through said pad.

Cap 116 which seals the top of column 26, is provided with upstanding air distributing section 183 (see Figs. 3 and 4) which in the main is cir-

cular and is slightly tapered from a point adjacent its base to its top. This section is provided with a circumferential groove 184 and with two vertically extending channels 185 and 186. Channel 186 communicates with groove 184 and channel 185 extends to and connects with a radially extending slot-like port 187.

A sleeve 188, having its interior bored on a taper to fit the tapered or frusto-conical surface of section 183, surrounds said section and is held in place thereon by means of a cap plate 189. This sleeve is provided with an annular pocket or depression 190 in its interior surface which registers with circumferential groove 184 to form an annular chamber with which pipe 121 connects. Said chamber is thus connected with the annular chamber formed in ring member 119 which is carried by the hub portion 62 of member 32 of the blank mold table as above pointed out.

Sleeve 188 on a level with port 187 is provided with six equally spaced ports 191, and each of these ports is tapped to receive a nipple 192. Hose sections 156 connect said nipples 192 with nipple 155 of the baffle assemblies. In other words, each hose section 156 connects one of the nipples 192 to one of the nipples 155.

Pipe 183 is connected to a suitable source of supply of air under pressure. This pipe is provided with a regulating valve 184 and is connected to vertical channel 186 by means of a T 185 and pipe section 186, and with vertical channel 185 by means of piping 197 which includes a valve 198 for controlling the air flowing through hose section 156. It will be apparent that as the blank mold table revolves about column 26 each of the baffle assemblies in turn will be supplied with air under pressure through its hose connection 156.

The blow or finishing mold table

The blow or finishing mold table 27 comprises a lower spider-like member 199, an intermediate member 200 and an upper member 201. These members are suitably secured together for rotation as a unit about column 28. Members 199 and 200 are supported on a lower anti-friction bearing 202 while upper member 201 is supported on an upper anti-friction bearing 202a. A ring gear 203 is carried by or forms part of spider-like member 199 and meshes with ring gear 34 of the blank mold table. As above pointed out, the blank mold table is driven by the finishing mold table, and spider-like member 199 of the finishing mold table carries rollers 204 and 205 which form part of the periodic motion drive mechanism by which the blow or finishing mold table is driven.

The finishing mold units, each of which as an entirety is numbered 206, are arranged in an annular series on the finishing mold table. Each unit includes a partible finishing mold 207 which rests upon a bottom plate holder 208, and the mold parts are connected by arms 209 to a vertical hinge pin 210. The mold, together with the bottom plate holder 208 and hinge pin 210 are mounted upon a vertically adjustable carrier 211 which more or less assumes the form of a slide mounted in a vertical slideway 212. Carrier 211 includes a threaded rod 213 actuated by a hand wheel 214 by which the finishing mold bottom plate holder, etc., are adjusted vertically relative to intermediate member 200 of the mold table upon which the mold opening and closing mechanism is mounted.

The mold opening and closing mechanism includes a pair of levers 215 connected through links 216 to the mold sections. Said levers are pivoted to a yoke 217 by means of vertical hinge pins 218. This yoke is directly connected to a push rod 219 (Fig. 13) which is slidably connected to a slide block 220 (Fig. 19) which carries a cam contact roller 221 adapted for engagement with a stationary cam 222 (Fig. 11). A coil spring 223 encircles push rod 219, is interposed between slide block 220 and yoke 217, yielding holds the yoke and slide block in their maximum spaced relation and provides yielding operating connection therebetween (Figs. 18, 19 and 20).

A sleeve 224 telescoping over a tubular portion of the slide block, surrounds a portion of the push rod and spring 223. This sleeve carries a spreader 225 designed for operative engagement with extensions 226 of levers 215 (Figs. 18 and 19). A coil spring 227 which encircles coil spring 223 is also enclosed by sleeve 224 and bears against the outer end of the tubular portion of slide block 220 and an internal shoulder 228 of sleeve 224 (Fig. 19). Spring 227 yielding holds the spreader and slide block in their maximum spaced relation and provides a yielding operating connection therebetween. By means of spring 227, the slide block operates to force the spreader 225 between and into engagement with extensions 226 of levers 215 (Fig. 18). Guide rods 229 mounted in upstanding brackets 230 (Fig. 12, lower portion) on intermediate member 200, slidingly support slide block 220, yoke 217 and spreader 225, and prevent movement of the parts about the axis of push 219.

The blow mold bottom mechanism is made up of three parts. The bottom plate holder 208 which is a horseshoe-shaped flat plate about five eighths of an inch thick, rests upon an angle plate bracket 208a carried by adjustable carrier 211. Bracket 208a forms a bearing for horizontal hinge pin 231 upon which an arm 208b is pivotally mounted. This arm carries mold bottom plug 232 which is held in place by means of a screw 208c having a knurled head as shown in Fig. 13. Bottom plug 232 projects above horseshoe-shaped plate 208 and swings downward through the action of toggle links 233 and connector rod 234. This connector rod is pivoted to a lever 235 which in turn is pivoted upon a horizontal hinge pin 236 carried by spider-like lower member 209 of the finishing mold table.

Lever 235 at its lower end carries a cam roller 237 which runs in a continuous stationary cam 238 by means of which the position of the bottom plug is controlled.

Each finishing mold unit 206 is provided with a blow head 239 which is carried by a holder 240 pivoted to a horizontal hinge pin (not shown) but which is axially aligned with and located between air boxes 241 and 241a (Fig. 14). Holder 240 is connected by a link 242 to one end of a bell crank lever 243 which at the other end carries a cam roller 244 arranged to cooperate with a stationary cam 245, to raise and lower the blow head at regular time intervals.

The blow head (Fig. 13) includes a mold sealing portion 246 which is adapted to rest upon the upper end of the finishing mold 207 and which is removably secured to the lower end of an outer externally threaded tubular member 247. Fitting within outer tubular member 247 is a tube-like liner 248. This liner at its upper end is provided with an outwardly extending flange 249 which

bears against the upper end of the outer tubular member 247. A head member 250 secured to outer tubular member 247 holds liner 248 in place. A hollow sleeve-like plunger 251 is mounted for sliding movement within liner 248. A stem-like member 252 which passes through an opening in head 250, at its outer end, carries a knob-like adjusting member 253. Intermediate 10 its ends, member 252 is provided with a flange 254 which forms an abutment for a coil spring 255 which surrounds the upper reduced end of hollow plunger 251. Below flange 254, member 252 threadedly engages hollow plunger 251. Coil spring 255, which is located between flange 254 and an inwardly extending flange 256 of liner 248, 15 yieldingly holds hollow plunger 251 at the upper limit of its travel as determined by the position of stem-like member 252 with relation to the hollow plunger.

Hollow plunger 251 at its lower end carries a 20 bottle top contact member or holder 257. This contact member is mounted for limited sliding movement within the plunger and is yieldingly held at the limit of its outward movement with relation to the plunger by a coil spring 258. This contact member is provided with a channel which extends therethrough from end to end, and its lower face is contoured to fit the upper end of the blank or parison.

A flexible air hose 259, by means of an elbow 260, nipple 261 and a channel 261' which passes downwardly through head 260, connects with the interior of the blow head above the effective portion of plunger 251. A flexible air hose 262 by means of an elbow 263, nipple 264 and an opening 265 formed in one side of plunger 251, connects with the channel which extends through contact member 257.

Air under pressure for blowing the parison to finished form is supplied through hose 262, while air under pressure for moving the plunger 251 down until its contact member 257 presses against the top of the blown article, and, steady- 40 ing the same, holds it in position on bottom member 232 of the blow mold, during opening of the mold and transfer of the ware is supplied by air hose 259.

Hose 259 connects with air box 241 while hose 262 connects with air box 241a. Boxes 241 and 241a and the hinge pin (not shown) upon which the blow head holder 240 is pivotally mounted, are carried by a yoke-like member 266 which is secured to or forms part of upper member 201 of the blow mold table.

Column 28, about which the blow mold table rotates, is sealed at its lower end by base 29 of the machine, and at its top by a cap 287 which forms part of an arm 268 of the take-off device 269.

Air under pressure is supplied to the interior of column 28, which serves as an air storage chamber, through a connection 270, and said column, in line with an annular groove 271 formed in the hub portion of table member 200, is provided with a series of openings 272 which establish communication between the interior of the column and said groove 271. Six equally spaced pipes 273 connect with said groove, and each, extending upwardly through a hole in member 200 of the mold table, connects with a port 274 of a control valve, which as an entirety is numbered 275. This valve controls the supply of air by way of pipes 276 and 277 to said air boxes.

The housing for valve 275 is made in two parts 278 and 279 bolted together as shown in Figs. 14 and 75.

and 16. Housing part 278 has a cylindrical bore for receiving a piston or slide valve made up of two parts 280 and 280a. Housing part 278 also has two ports 281 and 282 to which pipes 276 and 277 are respectively connected. The stem end of valve part 280, by means of a link 283, is connected to the free end of a lever arm 284. This lever arm is mounted on a post 285 secured to member 200 of the mold table, and, adjacent its center said lever arm carries a cam contact roller 286 which cooperates with a cam made up of parts 287 and 288. Cam part 287, as shown in Fig. 14, is rigidly secured to column 28 by a key 289, while cam part 288, is supported by part 287. Cam part 288 is provided with curved slots 290 for receiving pins 291 carried by cam part 287. This slot and pin connection between the cam parts permits relative angular adjustment of cam part 288 with relation to cam part 287.

Part 280 of the valve member, which is prevented from turning within the bore of the valve casing or housing by link 283, has a reduced portion 280b which joins part 280 with an abrupt shoulder 292. Portion 280b adjacent its outer end is externally threaded to receive the internally threaded end 293 of valve portion 280a. The inner end 294 of valve part 280a forms an abrupt shoulder, and the space between these shoulders forms the port of the valve member.

The outer end portion of valve part 280a is reduced in diameter as shown at 295, passes through an opening in the end of valve housing part 279, and at its outer end is provided with an adjusting knob 296. By means of this knob, valve part 280a may be screwed in or out with relation to valve part 280. In other words, by adjusting the position of part 280a with relation to part 280, the length of the valve port—that part of the valve member between the shoulder 292 and the end 294 of part 280a—may be varied.

In order to prevent accidental turning of valve part 280a, a hole for receiving a pin 297 is drilled radially through reduced part 295 of valve part 280a. Pin 297, therefore has end portions which extend beyond the surface of part 295. A collar 298 loosely surrounds part 295, has a depending portion 299 formed with wings 300 which underlie the edges of housing portion 279, and radial slots 301 in its end which faces pin 297. A coil spring 302 surrounds part 295 of the valve member, and, bearing at one end against collar 298 and at its other end against the outer end of valve housing 279, part 279 yieldingly forces said collar toward the valve part 280a. From this construction, it will be seen that as adjusting knob 296 is rotated, coil spring 302 causes collar 298 to lock part 280a of the valve in the position to which it is adjusted.

Adjustment and operation of the machine

Each blank mold reaches charging station I (line A) in inverted position (neck down) with its bottom up as shown in Figs. 1 and 9, but its baffle assembly instead of being above the mold as in said figures, is out of register therewith, as shown in Fig. 5 so that a mold charge may be dropped from any suitable feeding device into the open mold. A funnel (not shown) which is carried by a support arm 303 secured to the base 29 of the machine guides the charge into the open mold which is then stationary since the mold tables stop as each blank mold reaches charging station I. This is the beginning of the first indexing period.

When the blank mold is at rest at charging station I cam 127 through lever 128 and hollow

lever arm 96, is holding plunger 87 in its upper position against the stress of spring 91, so that the neck forming pin 88 is in position within the neck ring 88 to form the initial opening in the parison when the glass is packed around the same.

The neck ring or neck mold sections are embraced by the body mold sections and these in turn are locked in closed position by cam 74 through slide block 61, roller 72, pull rod 65, yoke 63 and links 64.

The turnover drum is locked in position not only by cam 48 and rollers 46, but by lock bar 59 under the urge of its coil spring 60. Cam 58 is so contoured as to permit (Fig. 7) roller 56 carried at the lower end of lever 53 to move inwardly toward column 26 allowing spring 60 to function.

Cam 125, which controls the operation of vacuum valve 102, is so contoured (Figs. 7 and 8) that said valve is opened as the blank mold reaches charging station I. This cam has an abrupt inclination at its entrance end 125a for roller 123a so designed as to quickly open the valve, and a much slighter inclination at its opposite end 125b for permitting the valve to be closed more gradually under the urge of its spring 108. It will thus be seen that the mold charge as soon as it enters the mold is subjected to vacuum, causing the molten glass to be packed around the neck forming pin 88.

Immediately upon the start of indexing (the blank mold table then moving in a counterclockwise direction), the baffle assembly, through rack bar 161 and gear segment 160, is swung in a clockwise direction from its position shown at station I, into alignment with the top of the blank mold. This is accomplished by double-faced cam 168 with which roller 167 engages (Figs. 1 and 5). Immediately after the baffle assembly is aligned with the top of the blank mold (this occurs on line B which is 20° after charging position) cam 188 through roller 178, plunger 177 and lever arm 134, moves baffle plate guide 147 down into sealing contact with the top (actually the bottom) of the blank mold with the baffle plate 133 remaining approximately $\frac{1}{4}$ inch above the upper surface of the blank mold at the top of the mold.

As soon as the baffle assembly reaches the position at which it is aligned with the top of the blank mold, the interior of the baffle assembly is connected to the blow down or packing air supply by means of flexible hose 156, so that this air is effective for packing the molten glass within the mold and around the neck forming plunger 88 as soon as the baffle plate guide 147 is in sealing contact with the annular shoulder at the top of the mold. This blow down or packing air which supplements the vacuum in forming the finish and mouth of the parison, is allowed to flow into the blank mold on top of the glass through channels 145 and 146 in the baffle plate 133, during 15° of table travel after the baffle guide reaches sealing position on the blank mold. This is because the width of port 187 in air distributing section 183 extends through 15° of table travel.

The baffle guide begins to move down into sealing engagement with the shoulder at the top of the mold as soon as the blank mold table has moved 20° from charging station I (line A), since at this position roller 178 begins to ride up cam 188. At 30° from charging station I, the baffle guide is brought into sealing contact and, at line D (45° from charging station I) cam 188 forces baffle plate 133 down until its bottom former portion 144 is in sealing contact with the top of the mold, in position for the bubble blow or parison

forming operation. Coil spring 158 which was compressed when the baffle guide was forced into sealing engagement with the annular shoulder on the top of the mold, is further compressed during movement of the baffle plate into sealing position with the upper surface of said annular shoulder.

With the finish and neck of the parison formed, the next in sequence is the "bubble blow" or parison forming operation. At this point, it must be assumed that cam 127, through lever 128, has moved hollow lever arm 96 up to position to carry mouth forming pin 88 into position to form the initial opening in the parison, and that said cam had moved lever arm 96 to a position such that coil spring 91 has retracted or moved down, mouth forming pin 88 into position for the bubble blow, the position shown in Figs. 2 and 9.

Air for effecting the bubble or parison forming blow in the blank within each blank mold unit is controlled by its air valve 100. This valve, through the agency of its plunger 105 and the adjustable stem 107 of said plunger is controlled by a cam, which as an entirety is numbered 124.

Cam 124 comprises two sections, a main full length section 124a and a shorter supplementary section or cam patch 124b. This cam patch is located alongside the main section 124a as shown in Fig. 7 and is connected thereto by slot and bolt connections as indicated in Fig. 8. This permits angular adjustment of the cam patch to different positions with relation to the main section.

The cam patch has an upwardly inclined entrance surface 124c, up which roller 123 of valve operating plunger 105 rides to the extreme top surface 124d of the cam, which top surface is flat. Main section 124a is provided with an exit surface 124e which includes downwardly from the top surface. The inclination of surface 124e is such that its drop is but very slight per inch of table travel.

The inclined entrance surface 124c determines the time during which valve 100 of each unit is being opened. This inclination is not critical, but the length of time that the air valve 100 of each unit remains open is critical, and, since different forming or mold units require different periods of time in which to effect the bubble or parison forming blow, I provide an independent adjustment for the air valve of each mold unit. The valve operating stem of each plunger 105 can be adjusted to vary the length of the gap between its upper end and the lower end of the valve stem. This provides the independent means for regulating the duration of the bubbles or parison forming blow of each mold unit in accordance with the requirements of such unit. The greater the length of this gap, the sooner will the valve close and conversely, the shorter the gap, the later will the valve close. This gap, of course, also varies the time the valve begins to open as its roller 123 rides up entrance incline 124c, but this incline is so steep that the variation caused by the length of the gap is negligible.

The slots in the cam patch are numbered 385, and the bolts which secure the cam patch to section 124a of the cam, can be located within any two suitable holes 386 in pads 387 formed on the inner face of section 124a in line with said slots.

Cam patch 124b can be so set as to allow full opening of valve 100 anywhere from 40° to 62° after start of an indexing period. I adjust the gap between stem 107 and stem 104 of each valve 100 to suit the requirements of the particular forming unit of which it forms a part.

Each roller 123 is located $12\frac{1}{2}^{\circ}$ behind the center line of its blank mold. In other words, each roller 123, during rotation of the blank mold table, lags $12\frac{1}{2}^{\circ}$ behind the center line of its blank mold.

In order to permit plunger 81 to be moved by coil spring 80 down to the position shown in Fig. 9, whereby contact between the glass and mouth forming pin 88 is broken, a cam patch 121a (Fig. 7) is employed. This cam patch is slideable in a circular slideway 308 secured to cam holder 304, and is held in place by means of bolts 309 which pass through the cam patch and slots 310 in the slideway.

This cam patch can be adjusted so as to start movement of lever arm 96 down to the position shown in Fig. 1 (left-hand side) from 30° to 69° after station I. This adjustment is provided in order to obtain time for proper set of the finish.

After roller 123 passes through the cam patch it engages wall 121b of cam 121 and this wall maintains contact between sealing head 126, carried by lever arm 96, and nipple 89 of plunger 81. This contact remains until 120° after charging station I, where roller 123 engages section 121c of cam 121. Lever arm 96 continues to move down until it reaches the position shown at the right-hand side of Fig. 1, so that clearance is allowed for the blow mold mechanism at the transfer point.

The mechanism controlling the bubble or parison forming blow can be so adjusted that said blow ends 21° before the blank mold unit reaches station III. At 21° before station III or 99° beyond station I (line A), the baffle plate is ready to rise out of contact with the top (bottom) of the blank mold, and requires 11° more of table travel to rise completely, at which time the blank mold will have traveled 110° from station I. Ten degrees before reaching station III the baffle assembly is raised high enough to clear the blank mold and is ready to swing away counter-clockwise from registry with the blank mold. Station III is a stop position and the end of the second index from charging station I. Two degrees after start of indexing or 122° beyond station I, the turnover drum is unlocked and is ready to be turned over by engagement of its rollers 46 with cam 47. The turnover drum of course uprights the blank mold, bringing the parison into upright position with its neck uppermost. The drum turning over operation requires 50° of table travel and the drum is completely turned over 172° from charging station I or 8° prior to the end of the third index. Locking of the turnover drum again takes place 177° after charging station I or 3° before the end of the third indexing period.

Eight degrees prior to station IV, the end of the third index, pressure of spring 88, holding the blank mold closed, will be practically released and the head 86 of pull rod 85 will be touching or just short of touching shoulder 83a of yoke 83, the blank mold remaining closed with the neck end of the parison up. At the start of the fourth index, the blank mold will begin to open and will be fully opened when it reaches line J, leaving the parison suspended by its finish in the neck mold.

The contour of cam 74 is such that the opening movements of the blank mold will allow clearance of the finishing or blow mold table 27 when the blow mold closes around the parison suspended by the neck mold which surrounds its finish.

At line J, that is 232° from charging station I, transfer of the parison to the blow mold is completed. Opening of the neck ring is accomplished by the outward radial movement of roller 83 occasioned by cam 84 (Fig. 7). This action causes spreader head 76 to rock and spread the neck mold halves to release the parison to the blow mold which is not in fully closed position, but is closed enough to support the parison by its finish bead.

Partial closing of the blow mold about the parison is so arranged that the parison will be held loosely until final closing of the blow mold. This loose holding offsets any misalignment which may occur between the neck ring and the blow or finishing mold, and prevents shear action between the neck ring and the blow or finishing mold. The entrance angle of cam 84 is very slight in order to provide this loose holding of the parison by the neck ring. Final release of the parison by the neck ring occurs at line J, so that the seams caused by the blank mold will match those made by the blow or finishing mold, thus preventing the possibility of two seams in the finished ware. This also insures the proper matching of oval or flat-sided parisons with the flat sides of the blow or finishing molds, when such articles as flasks or medical containers are being made. It, of course, will be understood that wider opening of the neck ring will be necessary for wide mouth jars, than for beer bottles or the like, and, to insure that proper opening of the neck ring will be effected on line J by cam 84, this cam is secured to stationary cam carrier 49 by means of slot and bolt connections, so that its angular position can be adjusted; said slots being numbered 84a (Fig. 7).

Turnbuckle 82 permits the making of different sizes of ware in the different blank molds of the same machine without changing the position of cam 84, since by means of the turnbuckle, the spacing between lever arms 80 and 81 can be varied to suit the ware being made in any particular blank mold. When the distance between these lever arms is shortened, the action of cam 84 will be delayed due to the fact that roller 83 will contact the entrance contour of cam 84 higher up on its angle. In other words, the shorter the distance between lever arms 80 and 81, the more space there will be between roller 83 and the minor radius of cam 84 and consequently a delayed action in opening the neck ring. This means that the turnbuckle will allow just enough separation of the neck ring parts to release the parison on line J. Thus, individual adjustment for each mold is obtained and this makes it possible to make different diameter and different shapes of ware at the same time, and to transfer or release the parison at the same point, that is on line J.

Line J is the line through the centers of the blank and finishing mold columns, and is 8° prior to the end of the fourth index or 232° from charging station I.

At 304° from charging station I, or 4° beyond station VI (end of fifth index) the blank molds are closed and at 318° beyond charging station I, the molds are locked and full pressure of coil spring 88 is applied. At 303° beyond charging station I, lobe 58 of cam 57 causes the turnover drum to be unlocked, thus allowing the turnover drum and the blank mold carried thereby to be reinverted by engagement of its rollers with cam 48.

Three hundred eighteen degrees after charg-

ing station I cam 127 causes bell crank lever 128 and hollow lever arm 86 to start to move plunger 87 upward. At 35° after charging station I upward movement of the plunger is completed, thus carrying mouth forming pin 88 into its upper position within the neck ring, that is, the position it occupies when the charge of glass is packed around the same to form the mouth of the bottle or ware.

The various portions of cam 127 are adapted to swing the lower end of bell crank lever 128 to different positions, toward and from column 28, and its movement at charging station I, toward column 28, is limited by an adjusting screw 311. Movement toward column 28 causes reverse movement of the upper end of said lever which carries yieldable plunger 128 and spring 132. The tension of this spring can be adjusted by means of an adjusting screw 312 (Fig. 1).

Sufficient movement of the lower end of bell crank lever 128 toward column 28 causes said lever and its link 121 to go into a toggled or locked position; the extent of movement being limited by adjusting screw 311.

When the blank mold reaches the charging station, the bell crank lever is in toggled position locking the plunger 87 at the upper limit of its travel with the mouth forming pin in operative position within the neck ring to form the mouth, or initial opening in the glass.

Retraction of the plunger is accomplished in two steps. In the first step, its movement is effected by adjustable cam patch 127a which can be so placed that said movement starts from 30° to 69° after start of the first index. As before pointed out, this first movement is just enough (3/8") to break contact between mouth forming pin 88 and the glass. After roller 128 passes through cam patch 127a it engages wall 127b which holds the blow head or sealing member 128 in contact with plunger 87. This contact remains for 120° after charging station I, at which point roller 128 engages cam section 127c which causes the second step movement to start, and this movement continues for 30° of table travel. During this movement, downward movement of plunger 87 is limited by contact of its upper flange 84 with shoulder 85 of sleeve 88.

As before pointed out, hollow lever arm 86, after leaving cam section 127c, contacts with exit cam section 127d which permits it to drop rather rapidly to the position shown on the right-hand side of Fig. 1, which position as before pointed out, allows clearance for the blow mold mechanism at the transfer point.

Roller 128a carried by plunger 108 which is located below the vacuum valve follows 15° behind the center line of the blank mold. This roller is moved up vertically by cam 125 to open the vacuum valve, so that said valve will be fully open 2° of table travel before reaching charging station I. Slots 125c through which bolts 125d pass secure the cam to the cam holder and permit angular adjustment of the cam with relation thereto. I adjust stem 111 of plunger 108 so as to obtain the gap between the upper end of stem 111 and the stem 112 of the vacuum valve 102 best suited to the individual mold unit of which such valve forms a part.

Fig. 14 of the drawings shows the normal setting of cam part 288 which is the limit of its clockwise adjustment. Each roller 286 precedes the center line of its companion finishing mold 287, 40° and in Fig. 14, roller 286 is shown by a dotted circle in the position it occupies when its 78

companion finishing mold is at the transfer position—the line through the centers of the blank and blow mold tables. No outward cam-occasional movement is imparted to roller 286 until it reaches a point 287a of cam part 287, at which point it receives an abrupt outward movement (radial movement away from column 28) and passes onto the cam contour extending from said point to point 287b. The outward radial movement imparted to the roller by contact with this contour is very slight per degree of table travel.

With the parts in the position shown in Fig. 15, (the position the parts are in before roller 286 reaches point 287a) ports 284 and 282 of valve 278 are shut off from communication with air supply pipe 273 for said valve. The construction is such that shoulder 292 cannot close off port 274 communicating with said air supply pipe. As before pointed out, the position of inner end 294 of valve part 280a with relation to shoulder 292 can be adjusted by turning adjusting knob 296.

The adjustment as to the time the air is allowed to pass from pipe 273 to pipe 277 for the blow, is dependent upon the adjusted position of shoulder 294 with relation to port 282. In other words, the shorter the adjusted distance between shoulder 292 and end 294 of valve part 280a the greater the distance the cam has to move the piston 280—280a, to open port 282, and, since the incline or throw from minimum to maximum radius of the cam requires table travel to bring roller 286 from point 287a to point 287b, it will be apparent that the relative adjustment of the piston or slide valve parts is ample to advance or delay the admission of air to blow the ware to finished form.

Air for operating bottle top contact member or holder 257 flows through port 284 and piping 278. When roller 286 reaches point 287c, valve 275 starts to close off the air for the finishing blow, and when said roller reaches point 287f, the finishing blow air is completely cut off, regardless of the adjustment of the valve. When said roller reaches point 287f, the finishing mold is at the point of table travel where it starts to open, and lever 284, which carries roller 286, will have moved shoulder 292 (toward the left Fig. 15) to uncover port 281, thus allowing air from pipe 273 to pass into the blow head to force bottle top contact member 257 into contact with the top of the bottle. This holds the bottle if it is sticking to the mold and steadies it and prevents it from shifting laterally on the mold bottom member 288.

Air flows through port 281 for a short time only or until the finishing mold is open enough to release the finished ware. At this time, roller 286 will have reached point 287g, at which point, the parts are returned to the position shown in Fig. 15 the air thus being shut off.

As before stated, cam part 288 by reason of its slots 290 can be adjusted to different positions with relation to cam part 287, and, if part 288 is adjusted counterclockwise as far as possible, blowing will be cut off when roller 286 reaches point 287d. However, the radius 287h prevents opening of port 281 until roller 286 reaches point 287e.

That part of the periodic motion mechanism of said patent by which I prefer to drive the finishing mold table of the machine of this application is more or less diagrammatically illustrated in Figs. 1 to 9 inclusive. Since the mold tables of this application are geared together, it is only necessary to make use of but one half of such mechanism, or that necessary for driving one table.

I prefer to construct the periodic motion mechanism so that its driving cams rotate 360° for each bottle or other piece of ware produced and so that 315° of this is taken up in table drive, leaving 45° of idle time for charging and takeout operations. This gives 12½% of each cycle for idle or down time and 87½% for driving.

In the machine of this invention, when driven by the mechanism of my said patent, the transfer of the parisons to the finishing mold is made while the tables are moving at or near their lowest peripheral speed and just before they stop at the station immediately adjacent the transfer point. This avoids distortion of the blanks or parisons such as occurs in continuously operating machines and still permits the mechanisms to be positively controlled and/or operated by cams instead of by air operated means.

The periodic motion drive mechanism disclosed in Figures 21 and 22 follows that disclosed in Figures 1 to 9 inclusive of my said patent and comprises a composite cam mounted for rotation on a standard 400.

A worm 402 mounted on a shaft 403 is driven by an electric motor 404 through a reduction gearing 405 and meshes with a worm wheel (not shown) secured to standard 400.

The composite cam, as in my said patent, comprises a heart-shaped cam member 406 which forms a support for cams 407 and 408. Cam 408 is offset from cam 406 and cam faces 408a and 408b thereof are approximately parallel with the adjacent face of cam 406 and co-operate with such cam in imparting movement to the blow or finishing mold table 27.

Periodic movement of the blow or finishing mold table is accomplished by cam contact rollers 204 and 205 carried by and depending from gear ring 203 which forms part of the blow or finishing mold table. Rollers 204 are arranged to contact with cams 406 and 408 while cam rollers 205 which rotate in a plane above rollers 204 are only capable of engaging cam 407.

This periodic motion mechanism accelerates the mold carrying tables of the machine when starting on an index and decelerates the tables toward the end of the index. In other words, the mold carrying tables are accelerated from a stop period or position to maximum speed and then decelerated to the next stop period or position. This mechanism also locks the tables against movement between indexing periods.

Having thus described my invention, what I claim as new and desire to secure by Letters Patent is:

1. In a glassware forming machine, two tables arranged side by side, mechanism for accelerating said tables from a stop period to maximum speed and then decelerating the same to the next stop period, a circular series of blank molds and associated neck molds carried by one such table, a circular series of finishing molds carried by the other table, mechanical means individual to each blank mold for opening and closing the same, a stationary cam common to such mechanical means and which is constructed and arranged to cause the same to open such blank molds adjacent the transfer point during decelerated movement of the tables, leaving the parison suspended by the associated neck mold, mechanical means individual to each finishing mold for opening and closing the same, a stationary cam common to such mechanical means and which is constructed and arranged to cause the same to open the finishing molds during such decelerated movement

and for partially closing the finishing mold around the suspended parison during such movement, and mechanical, cam operated means constructed and arranged to positively open each neck mold during such decelerated movement to release the parison to the finishing mold prior to the time the same has closed completely.

2. In a glassware forming machine, a mold table mounted for rotation about a vertical column and provided with a series of blank mold units, plunger mechanism associated with each mold unit for forming the initial opening in the blank and having passageways therethrough by which vacuum and air under pressure may be successively applied to the mold unit, a pivoted hollow arm associated with each blank mold unit for controlling the operation of said plunger mechanisms, spring closed vacuum and air valves for alternately connecting said arm to a vacuum and a pressure air supply, a stationary cam common to all said vacuum valves, a stationary cam common to all said air valves; said cams being arranged to open said valves, and means individual to each valve for adjusting its time of opening and closing independently of that of the other valves.

3. In a glassware forming machine, a mold table mounted for rotation about a vertical column and provided with a series of blank molds, plunger mechanism individual to each mold and having passageways through which vacuum and air under pressure are successively applied to the mold, a pivoted hollow arm individual to each mold, valves for alternately connecting said arm to a vacuum and a pressure air supply, a stationary cam for swinging said arms to control the operation of said plunger mechanisms, a cam for operating the vacuum valves, a cam for operating the air valves, and means individual to each valve and including an adjustable gap between such valve and its operating cam, whereby by adjusting the length of said gap the time of opening and closing of each valve can be adjusted independently of the opening and closing time of the other valves.

4. In a glassware forming machine, a mold carriage mounted for rotation about a vertical column and provided with a series of blank molds, plunger mechanism individual to each mold and having passageways through which vacuum and air under pressure are successively applied to the mold, a pivoted hollow arm individual to each mold, a stationary cam common to all said arms for swinging the same to control the operation of said plunger mechanisms, poppet valves for each mold unit for alternately connecting said arm to a vacuum and a pressure air supply, stationary cams for opening said valves, and a valve actuator individual to each valve and which is constructed and arranged so that the opening and closing time of each valve may be adjusted independently of the other valves.

5. In a glassware forming machine, a mold table mounted for rotation about a vertical column and provided with a series of blank molds, plunger mechanism individual to each mold and having passageways through which vacuum and air under pressure are successively applied to the mold, a pivoted hollow arm individual to each mold, a stationary cam common to all said arms for swinging the same to control the operation of said plunger mechanisms, poppet valves for each mold unit for alternately connecting said arm to a vacuum and a pressure air supply, stationary cams for opening said valves, and a valve actu-

ator individual to each valve and which is constructed and arranged so that the opening and closing time of each valve may be adjusted independently of the other valves; the cam for opening the air valves being provided with an abrupt entrance incline and an exit incline having a small drop per inch of travel of the mold table.

6. In a glassware forming machine and in combination with a blank mold unit and a baffle assembly, a support arm mounted for horizontal swinging movement and within which said assembly is mounted for vertical reciprocating movement, cam operated mechanical means for swinging said support horizontally to position said baffle assembly above said mold unit, a lever mounted for movement about a horizontal axis and movable with said support for reciprocating said baffle assembly toward and from said mold unit and cam operated mechanism including a stationary cam and a vertically movable actuator movable horizontally with said support arm and located between said lever and said cam for positively operating said means.

7. In a glassware forming machine, a rotatable mold table provided with a circular series of blank molds, plunger mechanism individual to each mold and having passageways through which vacuum and air under pressure are successively applied to the mold, a pivoted arm individual to each mold and having an air channel extending longitudinally thereof, a stationary cam common to all said arms for swinging the same to control the operation of said plunger mechanisms, poppet valves for each mold unit for alternately connecting said air channel to a vacuum and a pressure air supply, stationary cams for opening said valves, and a valve actuator individual to each valve and which is constructed and arranged so that the opening and closing time of each valve may be adjusted independently of the other valves; the cam for opening the air valves being provided with an abrupt entrance incline and an exit incline having a small drop per inch of travel of the mold table.

8. In a glassware forming machine, two tables arranged side by side, a periodic motion mechanism for accelerating such tables from a stop period to maximum speed and then decelerating the same to the next stop period, a circular series of blank molds and associated neck molds carried by one such table, a circular series of finishing molds carried by the other table, cam operated mechanical means for opening and closing the blank molds and which is constructed and arranged to open such molds during decelerated travel of the tables as each such mold approaches the transfer point, leaving the parison formed therein suspended by the associated neck mold, cam operated mechanical means for opening and closing each finishing mold and which is constructed and arranged to cause the finishing mold as it approaches the transfer point during decelerated travel of the tables to partially close around the suspended parison approaching the transfer point, and mechanical, cam operated means constructed and arranged to positively open each neck mold during such decelerated travel of the tables to release the parison suspended thereby to the closing finishing mold.

9. In a glassware forming machine, a series of invertible blank and associated blow mold units, a baffle assembly for each mold unit, an arm mounted for swinging horizontal movement about a vertical axis and having means thereon for mounting said baffle assembly for vertical move-

ment therein, a stationary cam for swinging such arm horizontally toward and from position above said mold unit, a lever connected to the baffle assembly and movable with said arm for reciprocating the baffle assembly vertically toward and from the mold unit and a stationary cam for reciprocating said lever.

10. In a glassware forming machine, an invertible blank and neck mold unit, a baffle assembly, a support arm mounted for horizontal swinging movement and within which said baffle assembly is mounted for vertical movement, a stationary cam for swinging said support arm toward and from position above said blank and neck mold unit, a lever mounted for movement about a horizontal axis and movable horizontally with said support arm for reciprocating said baffle assembly vertically within said arm, and a stationary cam constructed and arranged to swing said lever about said horizontal axis.

11. In a glassware forming machine, a mold table mounted for rotation about a vertical column and provided with a series of blank mold units, plunger mechanism associated with each such unit for forming the initial opening in the blank and having passageways therethrough by which vacuum and air under pressure may be successively applied to such unit, pivoted means individual to each mold unit and including an air channel connectable to said passageways, spring closed vacuum and air valves for alternately connecting said channel to a vacuum and a pressure air supply, a stationary cam common to all such vacuum valves and a stationary cam common to all such air valves; said cams being constructed and arranged to open said valves and means individual to each valve for adjusting its time of opening and closing independently of the other valves.

12. In a glassware forming machine, a mold table mounted for rotation about a vertical column and provided with a series of blank mold units, a plunger mechanism associated with each mold unit for forming the initial opening in the blank and having passageways therethrough by which vacuum and air under pressure may be successively applied to such mold unit, a pivoted arm associated with each mold unit for controlling the operation of its plunger mechanism and having an air channel as part for connecting said passageways to a vacuum and a pressure air supply, reciprocating spring closed vacuum and air valves for alternately controlling the vacuum and pressure air to such channel, a stationary cam common to all such vacuum valves, a stationary cam common to all such air valves; said cams being arranged to open said valves and means individual to each valve for adjusting its time of opening and closing independently of the other valves.

13. In a glassware forming machine, a mold table mounted for rotation about a vertical column and provided with a series of blank molds, plunger mechanism individual to each mold and having passageways through which vacuum and air under pressure may be successively applied to the mold, a swinging arm individual to each mold and having means for connecting such passageways with a vacuum and a pressure air supply, a stationary cam common to all such arms for swinging the same to control the operation of said plunger mechanisms, valves for each mold unit for alternately controlling the vacuum and pressure air supplied thereto, stationary cams for opening said valves, and a valve actuator individ-

ual to each valve and which is so constructed and arranged that the opening and closing time of each valve can be adjusted independently of the other valves; the cam for opening the air valves having an abrupt entrance incline and an exit incline having a small drop per inch of travel of the mold table.

14. In a glassware forming machine, an invertible blank and neck mold unit, a baffle assembly, a support arm mounted for horizontal swinging movement and within which said baffle assembly is mounted for vertical movement, a stationary cam for swinging said support arm toward and from position above said blank and neck mold unit, a lever mounted for movement about a horizontal axis and movable horizontally with said support arm for reciprocating said baffle assembly vertically within said arm, a stationary cam constructed and arranged to swing said lever about said horizontal axis, and manually operable means for adjusting the overall length of the baffle assembly to accommodate mold units of different lengths.

15. In a glassware forming machine, a rotatable mold table provided with a circular series of blank mold units, plunger mechanism associated with each mold unit for forming the initial opening in the blank and having passageways therethrough by which vacuum and air under pressure may be successively applied to the mold unit, pivoted mechanism individual to each mold unit for controlling the operation of the plunger mechanism and having an air channel as a part thereof, spring closed vacuum and air valves for alternately connecting said channel to a vacuum and pressure air supply, a stationary cam common to all said vacuum valves, a stationary cam common to all said air valves said cams being arranged to open said valves and means individual to each valve for adjusting its time of opening and closing independent of that of the other valves.

16. In a glassware forming machine, a rotatable mold carrier provided with a circular series

of blank molds, plunger mechanism individual to each mold and having passageways through which vacuum and air under pressure are successively applied to the mold, a pivoted arm individual to each mold and having an air channel extending longitudinally thereof, a stationary cam common to all said arms for swinging the same to control the operation of said plunger mechanisms, poppet valves for each mold unit for alternately connecting said air channel to a vacuum and a pressure air supply, stationary cams for opening said valves and a valve actuator individual to each valve and which is constructed and arranged so that the opening and closing time of each valve may be adjusted independently of the other valves.

17. In a glassware forming machine, two mold tables arranged side by side, an annular series of blank and associated neck molds on one such table, an annular series of finishing molds on the other table, table driving means for accelerating said tables from a stop period to maximum speed and then decelerating the same to the next stop period, cam operated mechanical means constructed and arranged to positively open each blank mold during movement of the tables and prior to the time each such mold reaches the transfer point, leaving the parison suspended from the associated neck mold, cam operated mechanical means constructed and arranged to positively open each finishing mold during movement of the tables and prior to the time each such mold reaches the transfer point and to partially close the same around the suspended parison during decelerated movement of the tables, and cam operated mechanical means constructed and arranged to open each neck mold to release the parison carried thereby to the closing finishing mold during decelerated movement of the tables and prior to the time the tables reach the next stop position immediately following the transfer point.
